BOAT HULL

Ian Proctor, Warsash, England, assignor to Richmond
Marine Limited, Sheen Lane, London, England

Filed June 29, 1967, Ser. No. 7,647

Claims priority, application Great Britain Jan. 3, 1967

Term of patent 14 years

Int. Cl. D12—06

U.S. Cl. D71—1

FIG. 1

FIG. 2

FIG. 1 is a side elevational view of a boat hull embodying my new design;

FIG. 2 is a top plan view thereof;

FIG. 3 is a longitudinal sectional view thereof on the line 3—3 of FIG. 2;

FIG. 4 is a transverse sectional view thereof on the line 4—4 of FIG. 3;

FIG. 5 is a transverse sectional view thereof on the line 5—5 of FIG. 3;

FIG. 6 is a transverse sectional view thereof on the line 6—6 of FIG. 3;

FIG. 7 is a front elevational view thereof; and,

FIG. 8 is a rear elevational view thereof.

I claim:

The ornamental design for a boat hull, substantially as shown.
